UNITED STATES PATENT OFFICE

154,561

DESIGN FOR A PUNCH AND RIVETING TOOL

Lawrence T. McNamara, South St. Paul, Minn.

Application October 12, 1946, Serial No. 133,905

Term of patent 3½ years

(Cl. D54—10)

To all whom it may concern:

Be it known that I, Lawrence T. McNamara, a citizen of the United States and residing in the city of South St. Paul, Dakota County, Minnesota, have invented a new, original, and ornamental Design for Punch and Riveting Tool, of which the following is a specification, reference being made to the accompanying drawing, forming a part thereof, wherein:

Fig. 1 is a perspective view illustrating a punch and riveting tool showing my new design, the upper jaw and handle lever being raised; and

Fig. 2 is a view in side elevation on a smaller scale showing the upper jaw and the handle lever in lowered position.

I claim:

The ornamental design for a punch and riveting tool, substantially as shown.

LAWRENCE T. McNAMARA.
